ARCHIBALD G. SHAVER, OF CHICAGO, ILLINOIS, ASSIGNOR TO CASALE SAFETY DEVICE COMPANY, OF NEW YORK, N. Y., A CORPORATION OF NEW YORK.

BRAKE-PIPE VALVE.

1,339,720.

Specification of Letters Patent. Patented May 11, 1920.

Application filed April 25, 1919. Serial No. 292,547.

To all whom it may concern:

Be it known that I, ARCHIBALD G. SHEAVER, a citizen of the United States, residing at Chicago, in the county of Cook and State 5 of Illinois, have invented certain new and useful Improvements in Brake-Pipe Valves, of which the following is a specification, reference being had therein to the accompanying drawing.

10 This invention relates to improvements in brake pipe valves, especially designed for use in connection with my co-pending train control applications, filed even date herewith, Serial Nos. 292,545 and 292,548, filed Apr. 15 25, 1919, one object of the invention being the provision of a simple construction of valve in which both electrical and pneumatic means are provided for controlling the flow of air for venting the air brake 20 system, in which a single casing carries the complete mechanism, and in which the parts thereof, due to any failure, will operate by gravity, this valve being primarily an air released valve while the valve shown in my 25 copending application, #292,549, is an air trapping valve.

A further object of this invention is the provision of a valve of this type which is simple and durable in construction and 30 which is positive in its function.

In the accompanying drawings is illustrated a transverse vertical central sectional view through the complete valve, showing the parts in normal condition when the coil 35 is energized.

Referring to the drawings, the numeral 1 designates the brake pipe which has connected thereto a nipple 2, a normally open valve 3, and a nipple 4, whereby the present 40 valve A is connected for controlling the flow of air to the exhaust of vent pipe 12. In this construction, the main body of the valve is cast and is provided with the receiving chamber 5, the auxiliary chamber 6, which is provided with a removable nozzle or bushing 7, which is made removable 45 so that different venting capacities may be employed.

The valve controlled port 8 leads from 50 the chamber 6 into the upper end of the chamber 9, whose lower end 10 permits the proper action of the piston 13, as will presently appear. In communication with the chamber 9 is the exhaust pipe 12. The valve 55 11 is normally held closed or upwardly by

means of the piston 13 while mounted upon its upper stem is the spring 11', which normally acts to open the valve. Leading from the lower end of the chamber 10 is a channel 14 which is in communication with the port 16, controlled at its opposite ends by means of the respective valves 15 and 17. In normal condition, the valve 17 is held in the position so that air is permitted to flow through the upper end of the port 16 to the channel 14 of the chamber 10. This causes the piston 13 to be elevated and holds the valve 11 seated. Thus air is prevented from entering the exhaust pipe 12.

Mounted in the lower end of the chamber 18 is the threaded boss 20 of the casing 21 which carries therein the magnet coil 23, the armature 22, and the valve operating stem 24, the cover 25 holding these parts in proper position and yet rendering them 75 accessible when necessary. When the coil 23 is deenergized and its armature 22 falls, the position of the valves 17 and 15 reverse, the upper end of the port 16 being closed so that the air in the chamber 10 is 80 permitted to escape through the channel 14, the port 16 into the chamber 18, and finally through the pipe 19 to the atmosphere. As pressure is thus permitted to exert itself upon the valve 11 and is also exerted by 85 upon the spring 11', the valve and piston 13 move downwardly, opening the port 8 and permitting air to be vented through the exhaust pipe 12.

The plug 26 is provided to permit access 90 to the plunger 13 in the valve 11, while the valve stem guiding plungers 27 and 28 are mounted in the casing to permit access to the stems of the valves 11 and 15. In order to permit access to the member 7 the 95 plug 29 is provided. The block 30 of insulation is attached to the casing of the main valve and has the conductors 31 and 32 leading therefrom and connected to the magnet coil 22.

It will thus be seen that with this construction the valves 15 and 17 will control the admission of air to controlling plunger 13 and thus when the coil is energized the valve 11 will be closed.

This construction of valve is readily connected to the train pipe of an air brake system so that under normal conditions the air is held against escape to the atmosphere, that is under conditions when the coil is 110

energized and air pressure is permitted to hold the valve 11 closed, the deenergization of the coil causing air to be shut off from the lower end of the piston and vented to the atmosphere so that the pressure above the valve 11 escapes and will cause the opening of the valve and the consequent exhausting of the train pipe to the atmosphere.

What I claim as new is:

- 5 16 1. A brake pipe valve, including a main member having three communicating chambers, the outlet between the second and third chambers being a valve port, said third chamber being provided with an exhaust port, an electrically controlled means for by-passing the air from the first chamber to the lower end of the third chamber, a valve for controlling the valve port, and a plunger connected to the valve and mounted in the 20 third chamber for actuating the valve.
- 15 2. A brake pipe valve, including a main member having three communicating chambers, the outlet between the second and third chambers being a valve port, said third chamber being provided with an exhaust port, an electrically controlled means for by-passing the air from the first chamber to the lower end of the third chamber, a valve for controlling the valve port, a plunger connected to the valve and mounted in the 25 30

the third chamber for actuating the valve, said electrical control means including two oppositely disposed valves connected for alternate movement, an electro-magnet, and means connected to the armature thereof and 35 to the valves for operating the valves.

3. A brake pipe valve, including a main casing having an air inlet and an air outlet, said casing being provided with three chambers interposed between said inlet and outlet and in communication with each other, the second and third chambers being in communication through a valve port, the third chamber constituting an exhaust and piston chamber, said casing being further 40 provided with a channel leading from the lower end of the third chamber and in communication with the first chamber, and the outside air, two valves one to permit communication between the first and third 45 chambers and the other to exhaust the third chamber to the outside air, a valve for controlling the first mentioned valve port, a piston mounted in the third chamber and connected to the valve and normally closed 50 by air pressure in the lower end of the chamber, and electrical means for operating the piston.

In testimony whereof I affix my signature.
ARCHIBALD G. SHAVER.
